UNITED STATES PATENT OFFICE.

BRUNO V. NORDBERG, OF MILWAUKEE, WISCONSIN.

STEAM-ENGINE.

1,241,875.

Specification of Letters Patent.

Patented Oct. 2, 1917.

Application filed April 16, 1914. Serial No. 832,192

To all whom it may concern:

Be it known that I, BRUNO V. NORDBERG, a citizen of the United States, residing at Milwaukee, in the county of Milwaukee and State of Wisconsin, have invented certain new and useful Improvements in Steam-Engines, of which the following is a specification, reference being had to the accompanying drawing, forming a part thereof.

10 This invention relates to single acting uniflow engines.

The main objects of the invention are to obtain a better and more economical action of the steam in the cylinder, to prevent as much as possible transmission of heat by conduction from the cylinder and by radiation from the piston to the engine frame, to enable the engine to run at a high speed, and generally to improve the construction 20 and operation of engines of this class.

It consists in the peculiar construction, arrangement and combination of parts as hereinafter particularly described and pointed out in the claims.

25 In the accompanying drawing like characters designate the same parts in the several figures.

Figure 1 is a vertical axial section of a vertical or upright cylinder engine embodying the invention; Fig. 2 is an enlarged partial cross section of the same on the line 2—2, Fig. 1; Fig. 3 is a similar section on the line 3—3, Fig. 1; and Fig. 4 is a section similar to Fig. 1 of a modified form of the engine in which steam is admitted to the lower instead of the upper end of the cylinder.

Referring to Figs. 1, 2 and 3, *a* designates the cylinder, provided at its upper end with an internally recessed head *b* and adjacent to its lower end with an annular exhaust port or series of ports *c*. A single acting reciprocating piston *d*, attached to a piston rod *e*, is formed or provided with a projection *f*, which fits into and nearly fills the cavity in the head *b* when the piston is at the upper limit of its movement. At the lower limit of its movement the piston is adapted to uncover the exhaust port *c* through which communication is established between the upper end of the cylinder and an exhaust belt or passage *g* surrounding the lower end of the cylinder in open and constant communication therewith. The exhaust belt or passage *g* communicates through a connection *h* on one side thereof, with a condenser (not shown),

by means of which a constant vacuum of from 24 to 26 inches is maintained when the engine is in operation. The exhaust belt or passage *g* may be formed as shown, with the engine frame *i* and the cylinder bolted thereto.

The piston rod *e* is connected in the usual manner with a cross head (not shown) guided in the frame, and passes through a stuffing box *j*, which prevents air from entering the space or passage *g* and impairing the vacuum therein.

The head *b* is formed with a cylindrical extension or valve seat *k*, through which an annular admission port or series of radial ports *l* lead inwardly into the cylinder or the upper end of the cavity in the cylinder head. A non-exhausting annular steam distribution valve *m* is fitted on the cylindrical extension or valve seat *k*, and is formed with an annular port or series of ports *n*, arranged to register with the admission port *l*. Upon the admission valve *m* is fitted a reciprocating annular cut-off valve *o*, the stroke or lap of which is varied by any suitable mechanism in a well known manner, according to the Meyer principle, to vary the point of cut-off.

The head *b* is formed above the piston cavity with a chamber *p* and with a seat for an upwardly opening relief valve *q*, which is guided in a flanged cap *r*, bolted to the upper end of the head.

The valve *q* is hollow, the interior cavity therein communicating with the chamber *p* through openings *s*, and a light spring *t* tends to hold it against its seat.

An upward cylindrical extension *u*, formed with or attached to the cylinder *a* and closed at its upper end by a head *v*, forms a steam admission and heating chamber *w*, surrounding and enveloping the head *b* and the valves *m* and *o*.

The cut-off valve *o* is formed with an upwardly projecting and outstanding annular deflector or shield *x*, and the extension *u* of the cylinder is formed in one side below the deflector or shield with a steam inlet opening and supply connection *y*. The deflector or shield *x*, over which the steam has to pass from the inlet opening *y* to the port *n* of the admission or distribution valve *m*, operates as a baffle to separate from the steam any water which may pass therewith into the chamber *w* or be formed by condensation therein, before it reaches said port.

The cylinder extension u is provided on one side with a drain connection z leading from the lower part of the chamber w and provided with a valve (not shown) for drawing off any water which may collect in said chamber.

The valve m is connected by a stem 2 passing through a stuffing box 3 in the head v , and by a spider 4 with any suitable actuating device (not shown) such as an eccentric. The spider 4, which is fixed on the stem 2, is loosely connected at the ends by pins 5, with inwardly projecting notched or slotted ears or flanges on the valve m , as shown in Figs. 1 and 3. This connection permits the valve to shift laterally with relation to the stem 2 and thereby adapt itself to its cylindrical seat on the head b without binding and without causing its stem to bind in its bearings.

The cut-off valve o is connected on opposite sides thereof with any suitable actuating device or mechanism (not shown) by rods or stems 6, passing through sleeve bearings 7 in the head v . These rods or stems are connected with the valve by pins 8 on which they have lateral play to permit the valve to work freely on the valve m without causing the rods or stems to bind in their bearings.

The annular ports c , l and n are formed at intervals with bridges or ribs as shown, and passages 9 are formed in the bridges or ribs of the port l , as shown in Fig. 2 and indicated by dotted lines in Fig. 1, for draining the chamber p and the cavity in the relief valve q and affording additional heating surface. The chamber p also communicates with the chamber w through openings 10 in the cap r , and through lateral openings 11 in the circular depending flange in which the valve q is fitted, with a space above said valve.

When the engine is in operation the chambers p and w and the cavity in the valve q are all filled with live steam which keeps the head b and the valve q , as well as the annular valves m and o hot. The steam in the clearance space between the cylinder head b , the valve q and the piston d , is thus exposed to highly heated surfaces, thereby securing efficiency and economy in its action in the cylinder, and enabling the engine to be run at a high speed.

The provision for effective draining keeps the surfaces to which the live steam is exposed dry and in the most effective condition for imparting heat to the steam in the clearance space.

With the arrangement shown and described the pressures acting on the piston produce no reversal of strains on the piston rod, but always act in the same direction, as indicated by an arrow on Fig. 1, both on the downward or working stroke and the upward or return stroke. At the end of the

working stroke, when the exhaust port c is uncovered by the piston the pressures above and below the piston are equalized, but on the upward or return stroke the steam in the space between the piston and head b is compressed while the vacuum is maintained below the piston. During the operation of the engine the vacuum which is constantly maintained in the lower end of the cylinder below the piston, obstructs the transmission of heat from the cylinder to the frame i to which it is attached.

In the operation of the engine the annular port n of the valve m at or near the lower limit of its movement, registers with the port l , and the ports n being then uncovered by the cut-off valve o , steam is admitted into the upper end of the cavity in the cylinder head when the piston is at the upper limit of its movement, flowing inwardly and radially into the space between the piston and the relief valve q , and downwardly and outwardly into the space between the piston and the head b . Upon the upward or return movements of the valves, the cut-off valve o , covering the port n at a variable point in the working stroke of the piston, shuts off the supply of steam to the cylinder according to the varying demand therefor and varying load on the engine. Before the piston passes below the exhaust ports c , the port n in the valve m is moved upwardly out of register with the port l in the head b . The steam confined in the cylinder escapes through the port c into the exhaust belt or passage g , a vacuum or partial vacuum being momentarily formed in the cylinder above the piston, and the pressure on the opposite ends of the piston being equalized or balanced.

Referring to Fig. 4, illustrating a modification of the engine in which steam is supplied to the lower end of the cylinder below the piston, the cylinder a' is closed at the lower end by an externally recessed head b' , which projects into the cylinder and fits into and nearly fills a corresponding cavity in the piston d' . The cylinder is formed with an exhaust belt or passage g' into which the annular exhaust port or series of ports c' opens, and which has on one side a condenser connection h' communicating also with the upper open end of the cylinder.

At its upper end the cylinder is bolted or attached to the frame i' , and the piston rod e' passing through a stuffing box j' in the wall between the cylinder and frame, is connected with a cross head 12, guided in the frame.

The head b' is formed with a central cylindrical cavity or valve chamber and seat k' and an annular port or series of radial ports l' leads therefrom into the cylinder. A non-exhausting annular steam distribution valve m' , fitted in the cylindrical chamber and seat k' in the cylinder head, con-

5 trols the admission of steam into the cylinder from a steam admission and heating chamber w' , which as shown, is formed in the cylinder head in communication with the lower end of the valve chamber k' , and communicates with a steam belt or passage u' surrounding the lower end of the cylinder and having a steam inlet opening and connection y' on one side.

10 The valve m' is connected with an eccentric or other suitable actuating device or mechanism (not shown) by a rod $2'$ passing through a stuffing box $3'$ in a removable cover v' with which the outer or lower wall 15 of the chamber w' is provided. A drain pipe or connection z' provided with a valve (not shown) leads from the lower part of the chamber w' .

This form of the engine is designed to be 20 set with the cylinder at an inclination, so that any water entering or forming, by condensation in the chamber w' can be completely drained therefrom through the pipe connection z' . The cylinder may however, 25 be set in a vertical position without materially affecting its drainage.

The operation and advantages of the construction last described are substantially like those of the construction shown by Figs. 30 1, 2 and 3, in which steam is supplied to the upper end instead of the lower end of the cylinder.

In both forms of the engine herein shown and described, it will be seen that an insulating space is provided 35 between the engine frame and the end of the cylinder opposite the steam admission end, and that when the engine is running, a constant vacuum is maintained in said space whereby transmission of heat from the cylinder and piston to the frame, and reversal of strains on the piston rod, are reduced.

Various modifications in details of construction and arrangement of parts other than those illustrated and specifically mentioned, may be made without departing from the principle and scope of the invention as defined in the following claims.

50 I claim:

1. In a steam engine the combination of a cylinder provided with an admission port at one end and an exhaust port adjacent to the other end which is in open and constant communication with an inclosed insulating space between it and the engine frame, a steam distribution valve controlling the admission port, a single acting piston adapted at the end of its working stroke to open the 55 exhaust port to the steam admission end of the cylinder, and means for maintaining a constant vacuum in the insulating space to which the inactive end of the piston is exposed.

65 2. In a steam engine the combination of

a cylinder having an admission port in the head at one end and an exhaust port adjacent to the other end which is in open and constant communication with an inclosed insulating space between it and the engine 70 frame, a steam heating chamber enveloping said cylinder head, a distribution valve controlling the flow of steam from said heating chamber through the admission port into the cylinder, a single acting piston 75 adapted at the end of its working stroke to open the exhaust port to the admission end of the cylinder, and means for maintaining a constant vacuum in said insulating space to which the inactive face of the piston is 80 exposed.

3. In a steam engine the combination of a cylinder provided with an exhaust port adjacent to one end which is in open and constant communication with an inclosed 85 insulating space, and at the other end with a head having a series of radial steam admission ports, a single acting piston adapted at the end of its working stroke to open the exhaust port to the admission end of the cylinder, said head and piston being formed one with a projection and the other with a corresponding cavity which is nearly filled by said projection at the end of the idle stroke of the piston, a steam heating chamber 95 enveloping the admission end of the cylinder, a distribution valve controlling the flow of steam from said chamber through the admission ports into the cylinder, and means for maintaining a constant vacuum 100 in said insulating space to which the inactive end of the piston is exposed.

4. In a steam engine the combination of a cylinder having an exhaust port adjacent to one end which is in open and constant communication with an exhaust connection and at the other end a recessed head provided with a series of radial admission ports opening into the recess therein, a steam heating chamber enveloping said head on 110 the outer side, a balanced annular valve controlling the admission of steam from said chamber through said radial ports into the cylinder, a reciprocating piston adapted at the end of its working stroke to open the exhaust port to the admission end of the cylinder, and means for maintaining a constant vacuum in the end of the cylinder to which the inactive end of the piston is exposed.

5. In a steam engine the combination of a cylinder having an exhaust port adjacent to one end which is in open and constant communication with an exhaust connection and at the other end a recessed head formed 125 with a series of radial admission ports opening into the recess therein, a steam heating chamber enveloping the outer side of said head, a reciprocating annular valve fitting over said head and controlling the admis- 130

- 4
- sion of steam from said chamber through said radial ports into the cylinder, a relief valve seated in said head inside of the annular series of admission ports, a single acting piston fitting into and nearly filling the recess in said head and adapted at the end of its working stroke to open the exhaust port to the admission end of the cylinder, and means for maintaining a constant vacuum in the end of the cylinder toward which the inactive end of the piston is presented.
- 5 6. In a steam engine the combination of a cylinder having an exhaust port adjacent to one end which is in open and constant communication with an exhaust connection and a head at the other end formed with an internal truncated conical cavity and with a series of radial admission ports leading inwardly from an outer cylindrical face into the smaller end of said cavity, a reciprocating annular valve fitting over the cylindrical face of said head, a steam admission and heating chamber enveloping said head and valve, a single acting piston adapted at the end of its working stroke to open the exhaust port to the admission end of the cylinder and having a truncated conical end projection fitting into and nearly filling the cavity in the cylinder head at the end of the return stroke of the piston, and means for maintaining a constant vacuum in the end of the cylinder toward which the inactive end of the piston is presented.
- 10 7. In a steam engine the combination of a cylinder having an annular exhaust port adjacent to one end, an inclosed insulating space in open and constant communication with said port and with the adjacent end of the cylinder, and at the other end a head formed with a cylindrical valve seat of smaller diameter than the bore of the cylinder, and a series of radial admission ports opening through said seat into the cylinder, an annular valve fitting said cylindrical seat and controlling said admission ports, a steam admission and heating chamber enveloping said head and valve, a single acting piston adapted at the end of its working stroke to open the exhaust port to the admission end of the cylinder, and means for maintaining a constant vacuum in said insulating space.
- 15 8. In a steam engine the combination of a cylinder having an annular exhaust port adjacent to one end, an inclosed insulating space in open and constant communication with said port and with the adjacent end of the cylinder, and at the other end a head formed with an internal cavity, a cylindrical valve seat on the outer side of smaller diameter than the bore of the cylinder, and an annular series of radial admission ports leading inwardly from said seat into said
- cavity, a reciprocating annular valve fitting said seat and controlling said admission ports, a steam admission and heating chamber enveloping said head and valve, a single acting piston adapted at the end of its working stroke to open the exhaust port to the admission end of the cylinder and having a projection which approximately fills the cavity in said head when the piston is at the end of its return stroke, and means for maintaining a constant vacuum in said insulating space.
- 20 9. In a steam engine the combination of a cylinder having an exhaust port adjacent to one end which is in open and constant communication with the exhaust connection and at the other end a head formed with an internal cavity, a relief valve chamber, an outer cylindrical face of smaller diameter than the bore of the cylinder, and a series of radial admission ports leading inwardly from said face into said cavity, a reciprocating annular admission valve fitting over said face and formed with ports adapted to register with said admission ports, a reciprocating annular cut-off valve fitting over said admission valve and controlling the ports therein, an outwardly opening relief valve seated in the chamber in said head, a steam admission and heating chamber enveloping said head and valves, a single acting piston adapted at the end of its working stroke to open the exhaust port to the admission end of the cylinder, and means for maintaining a constant vacuum in the end of the cylinder toward which the inactive end of the piston is presented.
- 25 10. In a steam engine the combination of an upright cylinder having an exhaust port adjacent to its lower end and at its upper end a head formed with an admission port, a valve controlling said port, an inclosed insulating space between the lower end of the cylinder and the engine frame in open and constant communication with that end of the cylinder toward which the inactive end of the piston is constantly exposed, a steam admission and heating chamber enveloping and extending below said head outside of the cylinder and having a drain connection leading from the lower part thereof a single acting piston adapted at the end of its working stroke to open the exhaust port to the admission end of the cylinder, and means for maintaining a constant vacuum in said insulating space.
- 30 11. In witness whereof I hereto affix my signature in presence of two witnesses.
